FORM FINISHER BAG

Bertram G. Blevens and Frank H. Richterkessing, Louisville, Ky., assignors to W. M. Cissell Manufacturing Company, Louisville, Ky., a corporation of Kentucky

Filed Jan. 4, 1966, Ser. No. 518,623

8 Claims. (Cl. 223—70)

This invention relates to a flexible bag for use with form finishers and more particularly to a bag which when inflated to selectively controlled maximum limits at its waist and hem lines may be employed for handling garments of a wide range of sizes.

When bags of voluminous size, for example, those capable of handling a size 44 dress are used, a problem of preventing wrinkling of the bag in its waist region with resulting wrinkling of the finished garment is likely when such a bag later is used in processing smaller garments. Also when different size garments whose scye openings are at different elevations with respect to the arm portions of the bag are to be handled, a problem of achieving optimum shaping of the bodice of the garment is found. Moreover, the ever-present considerations of preventing belling of the extremities of a garment and the tendency of the skirt of a dress to crawl along the bag must be considered. It is these and other problems confronted by the user of a form finisher which it is a purpose of our invention to overcome.

An object of the invention is to provide an improved form finisher bag capable of handling a large variety of sizes of garments and without imparting wrinkles to the finished garment in the waist region of the same.

Another object is to provide an improved form finisher bag capable of handling a large variety of sizes of garments and of shaping the bodice portion of the same with fidelity to the design of the bodice portion.

A further object is to provide a form finisher bag capable of handling a large variety of sizes of dresses and of shaping the skirts of such dresses in a generally cylindrical form.

Other objects and advantages will become more apparent as the description proceeds and when considered in conjunction with the accompanying drawings in which:

FIG. 1 is a perspective view of the bag in fully extended form and shown in position upon a form finisher.

FIG. 2 is a view showing a vertical section of the left hand side of the bag and with cooperating parts of a form finisher structure being indicated in elevation.

FIG. 3 is a view similar to FIG. 2 and showing the bag distended to accommodate a large size garment, a portion of which likewise is shown in section, and

FIGS. 4 and 5 are views similar to FIG. 3 and showing the positions occupied by the bag when accommodating medium and small size garments respectively.

Referring now to FIG. 1, the bag of the present invention, by way of illustration and not of limitation, is well suited for use with a form finisher structure of the type more fully disclosed and claimed in the copending application of Bertram G. Blevens, Ser. No. 485,338, filed Sept. 7, 1965, and assigned to the same assignee as the present invention. Such an apparatus includes a stationary housing 10 mounting a motor-driven blower 11 which forces air under pressure through conduit 12 and into a stationary base assembly having an annular wall 13 directing air upwardly into the bag. A conventional steam coil (not shown) is disposed within the base assembly for heating the air and is connected to a steam inlet line 14 and to a condensate return line 15.

A conventional steam column (not shown) which may be of the type shown in Richterkessing Patent No. 3,006,516 projects upwardly from the base assembly and is adapted to release steam within the bag under control

2

of a timer mounted on housing 10. Supported upon the steam column is a form finisher frame 16 of the type disclosed in said Blevens application and attached at its lower end to an annular wall 17 (FIG. 2) which is adapted to rotate with respect to the stationary wall 13. At the upper end of the frame a neck and shoulder element 18 is supported and over which the bag is draped.

The bag itself comprises generally an assembly of pieces of a suitable flexible fabric material, such as nylon, cut to a suitable pattern, and which are pervious to steam and to air. The bodice portion 20 is sewn along its lower peripheral edge to a bridging portion 21 which in turn is sewn along its lower peripheral edge to a relatively large diameter, elongated skirt portion 22. The skirt portion also is sewn along its lower peripheral edge to a bottom portion 23 the lower end of which is provided with a piping 24 in which a bag-fastening string is located. This string when fully tightened serves to hold the open lower end of the assembled bag in a groove 26 extending around the wall 17. By means of triangular pleats or darts 27 the diameter of the bottom portion is reduced from a maximum at its junction with the skirt portion to a minimum at its piping 24 thus to reduce the tendency of the bag to bell outwardly under the lower edge of the garment being processed thereon.

Referring now to FIGS. 1 and 2, the size of the bag may be conveniently adjusted for handling different sizes of garments by means of first and second drawstring arrangements which serve to define the size of the waist line of the bodice portion of the bag and the hem line of the skirt portion of the same. The first of these means may comprise a drawstring 30 encircling the outer periphery of the bodice portion 20 above the junction thereof with the bridging portion 21 and guided in loops 31 affixed to the outer surface of the bodice portion.

This first drawstring passes through an annular grommet 32 in the side of the bodice portion of the bag and is trained through a ring 33 attached to a pivoted arm 34 disposed within the bag, and after passing through the ring is attached to a suitable means as shown in said Blevens application for taking up or paying out the first drawstring in order to adjust the periphery of the waist line of the bag. In addition, a second drawstring 35 encircles the outer periphery of the skirt portion 22 adjacent its junction with the bottom portion 23 and is guided in loops 36 affixed to the outer surface of the skirt portion. This second drawstring passes through an annular grommet 37 in the side of the skirt portion and is trained through a ring 38 attached to a pivoted arm 39 disposed within the bag, and after passing through the ring is attached to a suitable means, as shown in said Blevens application, for taking up and paying out the second drawstring independently of the first drawstring and in order to adjust the periphery of the hem line of the bag.

As a significant feature of the present invention, an inner bag portion 40 is provided for assisting in the proper distention of the bag beneath the garment being processed thereon. This portion 40, which preferably is a separate piece of fluid-pervious flexible fabric having a somewhat greater porosity than the skirt portion of the bag, is sewn at its upper edge to the bridging portion 21 along a peripheral line or stitch 41 and also at its lower edge to the skirt portion 22 along a peripheral line or stitch 42. Alternatively, and without departing from the invention, the inner bag portion may comprise a part of the skirt portion in which event a separate portion of less porosity than the skirt portion may be used to form the material which is to contact the garment immediately below the waist line. In any event, the area of the inner bag portion disposed between lines 41 and 42 is substantially less than the area of the skirt and bridging portions disposed between those lines.

In a preferred form, the inner bag portion is also sewn to the skirt portion along an intermediate and third peripheral line or stitch 43 thus to divide the segregated upper part of the skirt portion into an annular section 44 and an annular section 45. Preferably, the lower section 44 when distended has a smaller volume than its companion section 45.

The bodice portion includes a pair of arm portions 50 and 51 to the outer ends of which are affixed complementary fastening elements 52 and 53. Conventional means, such as resilient bands 54 and 55, may be movably positioned upon the arm portions for suitable adjustment therealong to prevent belling around the ends of garment sleeves. As a feature of the invention, the bodice portion and the lower side of the arm portions are suitably cut away to provide scye openings 56 and 57, the significance of which will later appear. If desired, conventional suspender means 58 attached to its lower ends to the front and rear of the bodice portion, as indicated at 59, and draped over the neck and shoulder element 18, may be employed without detracting from the intended functioning of our improved bag.

The above-described voluminous bag is adapted to handle a variety of sizes of garments and when smaller garments are being processed a significant amount of excess bag material may be stored in the manner disclosed in the Blevens application by selectively lowering a storage ring 60 which in turn pulls into storage alongside the wall 17 a substantial area of the bottom portion 23 of the bag. Furthermore, when sleeveless garments are to be processed the arm portions of the bodice may be pulled inwardly through the scye openings and the elements 52 and 53 attached to each other, it being understood that the space needed for such manipulation is provided by the size used in the scye openings.

With the foregoing in mind, reference now is made to FIG. 3 showing a garment such as a woman's dress of large size in position upon the inflated bag. To distinguish the garment from the bag, a space is indicated therebetween and which, in actual practice, does not exist when the bag is inflated. As will be understood, the bag is deflated when the dress is placed thereon and then as processing fluids are supplied to the interior of the bag the following steps ensue. Inflation of the arm portions of the bag causes the arm portions of the dress, as seen at 61, to adopt their designed shape and likewise inflation of the bodice portion of the bag causes the bodice 62 of the dress to adopt its proper shape. Since drawstring 30 is holding the waist line of the bag at the proper elevation, the waist line of the garment is free to locate at its proper place on the bag.

When first placed on the bag the lowermost edge or hem 63 of the dress normally is below the lowermost edge of the inner portion 40 of the bag. As inflation of the bag occurs, the annular section 44 inflates simultaneously with the inflation of the upper, annular section 45 and, being confined by the enveloping dress, urges the section 45 into close contact with the skirt 64 of that dress below the waist line of the dress. Meanwhile, the lower part of skirt portion has inflated into frictional contact with the skirt of the dress and thus the dress does not tend to "crawl up" the bag. At this time the bridging portion 41 of the bag adjusts itself to the demands of the dress shape and prevents material of the dress from being trapped between the bodice and skirt portions of the bag. Accordingly, no wrinkles are formed in the dress in the region of its waist line while being processed on the bag. The invention is especially useful in processing dresses which require a generally cylindrical shaping of the skirt in order to accommodate fullness in the hip region of the dress.

As seen in FIG. 5, when a small dress is being processed on the bag the drawstrings 30 and 35 will first be pulled inwardly to decrease the waist and hem lines of the bag and the ring 60 will be lowered to store surplus material of the bottom portion 23 of the bag. As described with

respect to the assembly in FIG. 3, the annular sections 44 and 45 distend when fluid is supplied into the bag but to a much smaller extent. Under these conditions the bridging portion 41 adjusts itself to the smaller periphery of the smaller dress and substantially all of the fabric bag material constituting section 45 will be disposed below that bridging portion and will not be trapped in wrinkled condition at the waist line of the garment.

As shown in FIG. 4 wherein a dress of medium size is being processed, the bridging portion 41 likewise adjusts itself so that the annular section 45 may lift into close contact with the upper skirt portion of the dress and without being trapped between the dress and the bodice portion of the bag. In each of the illustrated dress sizes, the underarm portion of the scye line at the edge of the scye opening of the dress is free to seek its proper position in the cut-away bodice portion 20 and in the cut-away underarm portions of the sleeve 50 of the bag.

Having thus described our invention and its attendant advantages, it is intended that the appended claims are to cover such changes and modifications of the described bag structure as come within the true spirit and scope of the invention.

What is claimed is:

1. A form finisher bag comprising, a bodice portion, a skirt portion, a bridging portion connecting said bodice and skirt portions and serving to space the same from each other, a bottom portion connected to the lower edge of said skirt portion and serving to enclose the lower end of said bag, a first drawstring means for adjusting the waist line of said bag peripherally of said bodice portion and above said bridging portion, a second drawstring means for adjusting the hem line of said bag peripherally of said skirt portion and adjacent the junction of said skirt and bottom portions, and an inner bag portion extending peripherally of said bag and connected along a first peripheral line at its upper edge to said bridging portion and along a second peripheral line at its lower edge to said skirt portion and above the hemline of said bag, the area of skirt and bridging portions disposed between said first and second connecting lines being greater than the area of said inner portion disposed between said first and second connecting lines.
2. A bag as defined in claim 1 wherein said inner bag portion has a greater porosity to processing fluids than does said skirt portion.
3. A bag as defined in claim 1 wherein said inner bag portion is connected to said skirt portion along a third peripheral line intermediate said first and second peripheral lines thereby to divide the bag material exteriorly and circumferentially of said inner bag portion into two separate annular sections.
4. A bag as defined in claim 3 wherein the lower of said annular sections contains a smaller volume of space than the other annular section.
5. A bag as defined in claim 1 wherein said first and second drawstring means include first and second drawstrings respectively, encircling the outer peripheries of said bag at the waist and hemlines thereof and passing through apertures in said bag located adjacent the waist and hemlines of the bag.
6. A form finisher bag comprising, a bodice portion, a pair of arm portions extending outwardly from said bodice portion, said bodice portion and the adjacent underarm sections of said arm portions being cut away to provide scye openings in said bag and adapted to receive the underarm scye line sections of a variety of sizes of garments, a skirt portion, a bridging portion connecting said bodice and skirt portions and serving to space the same from each other, a bottom portion connected to the lower edge of said skirt portion and serving to enclose the lower end of said bag, a first drawstring means for adjusting the waist line of said bag peripherally of said bodice portion and above the bridging portion, and a second drawstring means for adjusting the hemline of

said bag peripherally of said skirt portion and adjacent to the junction of said skirt and bottom portions.

7. A bag as defined in claim 6 including fastening means at the outer ends of said arm portions adapted to connect with each other interiorly of said bag following the pulling of said arm portions inwardly through said scye openings of said bodice portion.

8. A hollow garment shaping bag for use on the frame of a garment finishing machine, said bag being formed of a flaccid, gas-pervious material and having bodice and tubular arm portions each adapted, under the influence of a processing gas introduced into the interior of the bag, to expand into contact with a garment placed thereon; the said bodice portion having an opening at each respective side of the shoulder portions thereof, each such opening forming the scye at which the respective arm portion is attached to the bodice portion and which arm portion is adapted, under the influence of the processing gas introduced into the bag, to extend outwardly from the bodice portion; the attachment of each arm portion at its scye being continuous across the top and along the upper side edges thereof and with the said arm por-

tion being unattached to the bodice portion across the bottom and along the lower side edges of its scye, said unattached portion providing an opening at the lower portion of the scye between the arm portion and the respective side of the bodice portion of the bag and into which last-mentioned opening the armpits of the sleeves of various garments having a size smaller than the maximum size of the bag may extend; thus to avoid wrinkling of the armpit portions of garments being finished upon the bag.
